TRANSFER NEEDLE FOR KNITTING MACHINES

Julius Sirmay, Philadelphia, Pa., assignor to
Ordnance Gauge Company, Philadelphia, Pa.,
a corporation of Pennsylvania

Application August 23, 1950, Serial No. 180,979

15 Claims. (Cl. 66—95)

1

The present invention relates to certain new and useful improvements in knitting needles and particularly to improvements in the stitch-transfer needles of automatic circular knitting machines.

An object of the present invention is to provide new and improved transfer needles for automatic circular knitting machines having a bank of dial-needles and a bank of cylinder-needles operatively co-acting, under certain conditions, to transfer stitches from one bank of needles to the other bank of needles.

Another object of the present invention is to provide a stitch-needle which will permit the free and easy transfer of stitches from a needle in one bank to a needle in another bank without the necessity for "racking" one bank of needles with respect to the other bank of needles and without the danger of the needles in one bank becoming jammed against or caught on the needles of the other bank.

A further object of the present invention is to provide a stitch-transfer needle which will be supported in the needle guide-groove of the knitting machine along the full length of the groove while yet providing means for spreading the yarn-loop to facilitate the transfer of the stitch from one bank of needles to the other bank of needles without the necessity of "racking" one bank of needles with respect to the other.

Another object of the present invention is to provide a stitch-transfer needle having lateral projections thereon to facilitate the transfer of the yarn from one needle to another; said lateral projections permitting a sliding contact between the needles without one needle becoming caught on the other.

Further objects will be apparent by reference to the appended specifications, claims and drawings.

For the purpose of illustrating the invention, there are shown in the accompanying drawings forms thereof which are at present preferred, although it is to be understood that the various instrumentalities of which the invention consists can be variously arranged and organized and that the invention is not limited to the precise arrangements and organizations of the instrumentalities as herein shown and described.

In the accompanying drawings wherein like reference characters indicate like parts:

Figure 1 represents a perspective view, on a greatly enlarged scale, of the stitch-receiving end of one embodiment of the transfer needle of the present invention.

2

Figure 2 represents a side elevational view of the yarn-spreading bridge of the transfer needle of Figure 1.

Figure 3 represents a bottom plan view of the stitch-transfer needle shown in Figures 1 and 2.

Figure 4 represents a cross-sectional view taken along line 4—4 of Figure 2.

Figure 5 represents a cross-sectional view taken along line 5—5 of Figure 2.

10 Figure 6 represents an end elevational view of the stitch-transfer needle of Figure 1.

Figure 7 represents a side elevational view of a dial transfer-needle and a co-acting cylinder transfer-needle of the present invention, operatively disposed in relation to each other at the beginning of the transfer operation.

Figure 8 represents a top-plan view of the stitch-transfer operation shown in Figure 7.

20 Figure 9 represents an end elevational view, partly in section, of a cylinder needle and a dial needle, shortly before the stitch-transfer operation moving the yarn from one needle to the other.

Figure 10 represents an end elevational view, 25 partly in section, taken generally along line 9—9 of Figure 7 showing the dial and cylinder needles a short time after the operation shown in Figure 9 and in the operative relationship disclosed in Figures 7 and 8.

30 Figure 11 represents an end elevational view, partly in section, of the operative relationship of the dial and cylinder needles a short time after the operation shown in Figure 10.

Figure 12 represents a perspective view of a 35 second embodiment of the transfer-needle of the present invention, viewed from the concave side of the bridge.

Figure 13 represents a side elevational view 40 of the needle of Figure 12 prior to the formation of the bridge.

Figure 14 represents a perspective view of the needle of Figures 12 and 13, viewed from the convex side of the bridge.

Figure 15 represents a side elevational view 45 of the needle of Figure 14 prior to the formation of the bridge.

Figure 16 represents a cross-sectional view along line 16—16 of Figure 13.

Figure 17 represents a cross-sectional view 50 along line 17—17 of Figure 15.

Figure 18 represents a cross-sectional view along line 18—18 of Figure 14.

Figure 19 represents a cross-sectional view 55 along line 19—19 of Figure 12.

Figure 20 represents a fragmentary perspective

view of the bridge of another embodiment of the present invention.

Figure 21 represents a cross-sectional view on line 21—21 of Figure 20.

In the operation of automatic circular knitting machines, the use of stitch-transfer needles (in the bank of dial needles and in the bank of cylinder needles) having lateral projections adapted to facilitate the transfer of yarn from one bank of needles to the other bank of needles is shown in the art. However, the needles of the prior art have been unsatisfactory inasmuch as the strength of these needles was sacrificed in producing the cam-like yarn-spreading projection extending across the side of the needle and by necessitating the use of a guide-groove for the needles in both the cylinder and dial banks which did not support the body of the needle along the entire length of the groove.

The needle of the present invention is adapted to facilitate the transfer of stitches from one bank to the other without "racking," while being supported along the entire length of the guide-groove, and has a cam-like lateral projection adapted to spread the yarn-loop to permit the entry of a co-acting needle into said loop and transfer the stitch therefrom. Moreover, the needle of the present invention is adapted to permit another needle to slide past without becoming jammed or interlocked against the lateral projections thereof; all without the necessity of "racking" the needles in one bank with respect to the needles in the other bank.

The transfer needle 15 of the present invention has a body portion 16 having a thickness 17 and a width 18 and terminates at one end in a reduced portion 19 and a yarn-receiving hook 20.

To the rear of the hook 20 is the laterally offset camming-portion or bridge 21, formed integrally with the body portion 16 and interconnected therewith at the ends 22 and 23.

The maximum lateral projection of the bridge 21 is indicated by the arrows 24 and is sufficient (as is shown particularly in Figure 8) to permit the hook of a stitch-receiving needle 25 to pass upwardly between the side surface 26 of the body-portion 16 and the inner concave surface 27 of the bridge 21, and also to spread the yarn 28 so that the stitch-receiving needle 25 easily may engage the loop of the yarn which is caught on the bridge 21 (see Figures 7 and 8).

The bridge 21 may be formed by pressing the needle between suitable dies (such as coining dies, or the like) to shear the body-portion along lines 29, 30, and 31 and to push the bridge laterally outward from the side of the body portion.

The bridge 21, intermediate its ends 22 and 23 is formed with an abutment 32 disposed generally at right angles to the longitudinal axis of the needle, to provide a stitch-receiving surface or shoulder to catch the yarn during the knitting operation, as is shown particularly in Figures 7 and 8. Directly forward of the abutment 32 on the bridge 21 a slight hump 33 may be formed to provide a generally V-shaped notch 34 adapted to retain the yarn-loop 28 on the loop-spreading bridge 21.

The thickness 17 of the body-portion 16 is not increased in the area 35, near the bottom edge 35 and thus, the guide-groove (not shown) in the cylinder or dial of the knitting machine can be substantially the same width as the needle-width 17 along its entire length.

Beneath the bridge 21, along a portion of the

corner of the body-portion 16 which interconnects the bottom edge 35 and the side face 26 is an inclined camming surface 37, cut in the body-portion 16 as by milling or grinding or the like. The camming surface 37 reduces the thickness of the bottom edge 35 enough to guide the hook 38 of a stitch-receiving needle (moving in alignment therewith, as is shown in Figure 9) against and to the side-face 26, without "racking," to prevent the needles from becoming jammed together and bent out of shape.

A continued move of the stitch-receiving needle 25 with respect to the stitch-transfer needle 15 brings the hook-portion 38 of the stitch-receiving needle between the face 26 of the body-portion 16 and the face 27 of the bridge 21 (see Figure 7). Thereafter, as the stitch-transfer needle 15 moves forwardly in the direction of the arrow 39, the stitch-receiving needle 25 engages the loop 28 of the yarn, as at 40 in Figure 7.

The relative lateral position of the two needles at this stage of the stitch-transfer is shown in Figure 10.

So that the stitch-receiving needle 25 may securely engage the loop 28 of the yarn in the hook-portion 38 thereof, the needle 25 may move upwardly in the direction of the arrow 41 (with respect to the stitch-transfer needle 15).

A camming surface 42 in the rear portion of the bridge 21 is adapted to guide the hook 38 of the stitch-receiving needle 25 during the rearward movement of the needle; i. e., in the opposite direction from the arrow 39 toward the outer side-surface 43 of the bridge 21.

The camming of the needle 25 by the surface 37 and the surface 42 springs the stitch-receiving needle 25 slightly, as is shown in Figure 11, and permits the by-passing of the needles without the necessity for "racking" one bank of needles with respect to the other bank of needles.

When the stitch-transfer needle 15 is retracted (in the direction opposite to that of the arrow 39) the elevated stitch-receiving needle 25 slides past the bridge 21 and the hook 38 of the needle 25 securely engages the loop 28 of the yarn where it rests in the V-shaped groove 34.

To enable the inclined stitch-receiving needle 25 freely to pass the corner 44 of the bridge 21, an additional camming or inclined surface 45 is provided in the outer surface 43 of the bridge 21. As the needle 15 moves rearwardly and the needle 25 slides along the bridge 21, the hook 38 does not strike the corner 44, whereby to permit proper transfer of the stitch from one needle to the other without damage to said needles.

Thereafter, the stitch-transfer needle and the stitch-receiving needle may be fully retracted in their respective guide-grooves, to complete the transfer of the yarn 28 from one needle to the other.

With the needle of the present invention it is unnecessary to disconnect either the end 22 or the end 23 of the bridge 21 from the body portion 16 of the needle and, moreover, it is unnecessary to limit the maximum rise of the needle 25 with respect to the needle 15, as has been heretofore the case (heretofore said stitch-receiving needle 25 having a maximum rise limited by the position of the edge 31 of the bridge 21). When using the needle of the present invention, the hook-portion 38 of the stitch-receiving needle may rise upwardly as far as is necessary adequately to engage the yarn 28—being generally somewhat above the V-shaped groove 34.

Moreover, the inclined camming surfaces 37,

42 and 55 spring the stitch-receiving needle 25 to the side of the stitch-transfer needle 15 without "racking" or otherwise shifting the needles and without the danger of one needle striking the other and damaging the same.

It is to be understood that the camming surfaces 37, 42, and 45 may be of such size and angularity as adequately to permit the by-passing of the needle 25 with respect to the needle 15.

Moreover, the V-shaped groove between the 10 abutment 32 and the hump 33 on the bridge 21 retains the loop of yarn 28 on the needle 15 until it is firmly dislodged therefrom by the hook 28 of the needle 25.

The second embodiment of the transfer-needle 15 of the present invention, shown in Figures 12 to 19 inclusive, is similar to the embodiment disclosed in Figures 1 to 11 inclusive except for the camming-surfaces formed on the bridge 46.

One camming surface 47 is formed in the body-portion 16 prior to the formation of the bridge 46—i. e. prior to the formation of the bridge 46 by pressing laterally the material of the bridge with respect to the body-portion 16. This is shown particularly in Figures 13 and 16. The 23 camming portion 47 may be formed by bringing the rotating edge of a hemi-spherical or frusto-conical milling cutter or grinding wheel against the side 49 of the body-portion 16 and cutting a groove therein along the line 48, as shown in 30 Figures 13 and 16, with the point of deepest penetration of the cutting wheel passing through the needle substantially to the other surface 26 of the body-portion 16.

Thus, there is formed an inclined surface 47 35 in the body-portion 16 between the arrows 50, and generally vertically above the inclined camming surface 37, heretofore described.

On the other side of the needle 15 (i. e., in the face 26 thereof) another camming surface 51 40 is cut, prior to the formation of the bridge 46, in substantially the same manner as the camming surface 47.

After the grooves 47 and 51 have been formed in the opposed surfaces 49 and 26, respectively, 45 the bridge 46 may be pressed laterally from the plane of the body-portion 16 by shearing along the lines 48 and 52 and pressing the bridge 46 laterally to one side of the plane of the body-member 16.

The camming surface 47 then is disposed on the concave side of the lower edge of the bridge 46 and (as is shown in Figure 18).

The camming surface 47 guides the hook 38 of the needle 25 into the space between the concave surface 27 of the bridge 46 and the side-surface 26 of the needle 15 where it can engage to loop of yarn 28.

Thereafter, when the needle is moved ahead and the needle 25 rises from the position shown 60 in the dash-dot line indicated at 49 in Figure 7, the needle 25 may be guided by the inclined surface 51 outwardly to the convex side of the bridge 46, as is shown in Figure 11.

Thus, the camming surfaces 47 and 51 may 65 be cut in the body-portion 16 (and particularly in the bridge portion 46) prior to the formation of the bridge 46.

The position and depth of the grooves which 70 form the inclined camming surfaces 47 and 51 may, of course, be selected so that, after the bridge 46 is formed in the needle, the inclined camming surfaces 47 and 51 will be properly disposed with respect to the edges 48 and 52, so that a needle coming into juxtaposition with the 75

transfer-needle 15, in the area of the bridge 46, will be guided properly into position without striking or becoming jammed against the body-portion 16 or the bridge 46 and permit easy, trouble-free passing of the co-acting needles.

In other respects, the needle shown in the embodiment of Figures 12 to 19 inclusive is similar to the needle described with respect to Figures 1 to 11 inclusive.

The embodiment shown in Figures 20 and 21 is generally similar to the embodiment shown in Figures 12 to 19 inclusive, with the exception that the camming surface 51 is omitted. During the formation of the bridge 46 (as by stamping, pressing, or forming in a coining die) the rear portion 60 of the bridge 46 (i. e. that portion of the bridge 46 to the rear of the shoulder 32) is twisted or inclined, as is shown particularly in Figure 21. Thus, the rear portion 60 of the bridge 46 is twisted so that the outer surface 61 is inclined outwardly and upwardly (from the bottom edge 62 to the top edge 63) so that the entire side-surface 61 of the rear portion 60 presents an outwardly and upwardly inclined camming surface in the convex side of the bridge 46. Thus, the side-surface 61 provides an inclined camming surface similar to the camming surface 51 in the embodiment of the needle shown in Figures 12 to 19 inclusive.

Thus, a camming surface is provided in the convex side of the bridge without reducing the strength of the bridge or the needle by grinding or milling a groove into the body-portion of the needle. In addition, if desired, the cross-sectional area of the rear portion 60 of the bridge 46, where it joins the body-portion 16 of the needle, may be increased in size so as to provide a sturdier intersection between the bridge and the body-portion whereby to permit the twisting of the rear portion 60 without breaking the bridge loose from the body-portion 16 at the rear merger point or juncture zone.

In other respects, the needle of the embodiment shown in Figures 20 and 21 is similar to the needle shown in Figures 12 to 19 inclusive.

The present invention may be embodied in other specific forms without departing from the spirit or essential attributes thereof, and it is therefore desired that the present embodiments 50 be considered in all respects as illustrative and not restrictive, reference being had to the appended claims rather than to the foregoing description to indicate the scope of the invention.

Having described my invention, what I claim as new and desire to protect by Letters Patent is the following:

1. A stitch-transfer knitting-needle for use in automatic knitting machines, said knitting-needle having a hook and a body-portion, a bridge projecting laterally from one side-surface of said body-portion and being integrally united therewith at its ends and spaced therefrom in the intermediate zone, said bridge having an abutment disposed at an angle to the longitudinal axis of said needle whereby to provide a yarn-retaining shoulder on said bridge, at least one inclined camming surface formed in the outer side of said bridge, and an inclined camming surface formed in the body-portion of said needle generally beneath said bridge.

2. A stitch-transfer knitting-needle for use in automatic knitting machines, said knitting-needle having a hook and a body-portion, a bridge projecting laterally from the upper half of one side-surface of said body-portion and being in-

tegrally united therewith at its ends and spaced therefrom in the intermediate zone, said bridge having an abutment disposed at an angle to the longitudinal axis of said needle whereby to provide a yarn-retaining shoulder on said bridge, at least one inclined camming surface formed in the outer side of said bridge, and an inclined camming surface formed in the body-portion of said needle generally beneath said bridge.

3. A stitch-transfer knitting-needle for use in automatic knitting machines, said knitting-needle having a hook and a body-portion, a bridge projecting laterally from one side-surface of said body-portion and being integrally united therewith at its ends and spaced therefrom in the intermediate zone, the rear end of said bridge integrally connected to said body-portion above the point of connection of the front end of said bridge to said body-portion, said bridge having an abutment disposed at an angle to the longitudinal axis of said needle whereby to provide a yarn-retaining shoulder on said bridge, at least one inclined camming surface formed in the outer side of said bridge, and an inclined camming surface formed in the body-portion of said needle generally beneath said bridge.

4. A stitch-transfer knitting-needle for use in automatic knitting machines, said knitting-needle having a hook and a body-portion, a bridge projecting laterally from one side-surface of said body-portion and being integrally united therewith at its ends and spaced therefrom in the intermediate zone, said bridge having an abutment disposed at an angle to the longitudinal axis of said needle and having a raised portion between said hook and said abutment whereby to provide a yarn-retaining notch on said bridge, at least one inclined camming surface formed in the outer side of said bridge, and an inclined camming surface formed in the body-portion of said needle generally beneath said bridge.

5. A stitch-transfer knitting-needle for use in automatic knitting machines, said knitting-needle having a hook and a body-portion, a bridge projecting laterally from one side-surface of said body-portion and being integrally united therewith at its ends and spaced therefrom in the intermediate zone, said bridge having an abutment disposed at an angle to the longitudinal axis of said needle whereby to provide a yarn-retaining shoulder on said bridge, at least one inclined camming surface formed in the outer side of said bridge, an inclined camming surface formed on the inner side of said bridge, and an inclined camming surface in the body-portion of said needle generally beneath said bridge.

6. A stitch-transfer knitting-needle for use in automatic knitting machines, said knitting needle having a hook and a body-portion, a bridge projecting laterally from one side-surface of said body-portion and being integrally united therewith at its ends and spaced therefrom in the intermediate zone, said bridge having an abutment disposed at an angle to the longitudinal axis of said needle whereby to provide a yarn-retaining shoulder on said bridge, at least one inclined camming surface formed in the outer side of said bridge, and an inclined camming surface formed in the body-portion of said needle generally beneath said bridge, the inclined camming surface on said bridge adapted to guide a co-acting stitch-receiving needle past said bridge during the stitch-transfer operation.

7. A stitch-transfer knitting-needle for use in automatic knitting machines, said knitting-needle

having a hook and a body-portion, a bridge projecting laterally from one side-surface of said body-portion and being integrally united therewith at its ends and spaced therefrom in the intermediate zone, said bridge having an abutment disposed at an angle to the longitudinal axis of said needle whereby to provide a yarn-retaining shoulder on said bridge, at least one inclined camming surface formed in the outer side of said bridge, and an inclined camming surface formed in the body-portion of said needle generally beneath said bridge, said bridge providing a yarn-loop-spreading projection of sufficient lateral dimension to permit the hook of a stitch-receiving needle to enter a yarn-loop engaged on said abutment and to remove the yarn-loop from said transfer-needle.

8. A stitch-transfer knitting-needle for use in automatic knitting machines, said knitting-needle having a hook and a body-portion, a bridge projecting laterally from one side-surface of said body-portion and being integrally united therewith at its ends and spaced therefrom in the intermediate zone, said bridge having an abutment disposed at an angle to the longitudinal axis of said needle whereby to provide a yarn-retaining shoulder on said bridge, at least one inclined camming surface formed in the outer side of said bridge behind said abutment, and an inclined camming surface formed in the body-portion of said needle generally beneath said bridge.

9. A stitch-transfer knitting-needle for use in automatic knitting machines, said knitting-needle having a hook and a body-portion, a bowed bridge projecting laterally from one side-surface of said body-portion and being integrally united therewith at its ends and spaced therefrom in the intermediate zone, said bridge having an abutment disposed at an angle to the longitudinal axis of said bridge, at least one inclined camming surface formed in the outer side of said bridge, and an inclined camming surface formed in the body-portion of said needle generally beneath said bridge.

10. A stitch-transfer knitting needle for use in automatic knitting machines, said knitting-needle having a hook and a body-portion, a concavo-convex bridge projecting laterally from one side-surface of said body-portion and being integrally united therewith at its ends and spaced therefrom in the intermediate zone, said bridge having an abutment disposed at an angle to the longitudinal axis of said needle whereby to provide a yarn-retaining shoulder on said bridge, at least one inclined camming surface formed in the convex side of said bridge, and an inclined camming surface formed in the body-portion of said needle generally beneath said bridge.

11. A stitch-transfer knitting-needle for use in automatic knitting machines, said knitting-needle having a hook and a body-portion, a bridge projecting laterally from one side-surface of said body-portion and being integrally united therewith at its ends and spaced therefrom in the intermediate zone, said bridge having an abutment disposed transversely to the longitudinal axis of said needle whereby to provide a yarn-retaining shoulder on said bridge, at least one inclined camming surface formed in the outer side of said bridge, and an inclined camming surface formed in the body-portion of said needle generally beneath said bridge.

12. A stitch-transfer knitting-needle for use in automatic knitting machines, said knitting-

needle having a hook and a body-portion, a bridge projecting laterally from one side-surface of said body-portion and being integrally united therewith at its ends and spaced therefrom in the intermediate zone, the inner surface of said bridge being spaced laterally at least the thickness of one needle from the side-surface of said body-portion adjacent said bridge, said bridge having an abutment disposed at an angle to the longitudinal axis of said needle whereby to provide a yarn-retaining shoulder on said bridge, at least one inclined camming surface formed in the outer side of said bridge, and an inclined camming surface formed in the body-portion of said needle generally beneath said bridge.

13. A stitch-transfer knitting-needle for use in automatic knitting machines, said knitting-needle having a hook and a body-portion, a bridge projecting laterally from one side-surface of said body-portion and being integrally united therewith at its ends and spaced therefrom in the intermediate zone, said bridge having an abutment disposed at an angle to the longitudinal axis of said needle whereby to provide a yarn-retaining shoulder on said bridge, at least one inclined camming surface formed in the outer side of said bridge, and an inclined camming surface formed in the body-portion of said needle generally beneath said bridge, said bridge behind said abutment being twisted with the outer surface thereof being disposed at an angle to the side-surface of said body-portion to form said inclined camming surface in the outer side of said bridge.

14. A stitch-transfer knitting-needle for use in automatic knitting machines, said knitting-needle having a hook and a body-portion, a bridge projecting laterally from one side-surface of said body-portion and being integrally united therewith at its ends and spaced therefrom in the intermediate zone, said bridge having an abutment disposed at an angle to the longitudinal axis of said needle whereby to provide a yarn-retaining shoulder on said bridge, at least one inclined

camming surface formed in the outer side of said bridge, and an inclined camming surface formed in the body-portion of said needle generally beneath said bridge, said bridge behind said abutment being twisted about an axis substantially parallel with the longitudinal axis of said needle and with the outer surface thereof being disposed at an angle to the side-surface of said body-portion to form said inclined camming surface in the outer side of said bridge.

15. A stitch-transfer knitting-needle for use in automatic knitting machines, said knitting-needle having a hook and a body-portion, a bridge projecting laterally from one side-surface of said body-portion and being integrally united therewith at its ends and spaced therefrom in the intermediate zone, said bridge having an abutment disposed at an angle to the longitudinal axis of said needle whereby to provide a yarn-retaining shoulder on said bridge, at least one inclined camming surface formed in the outer side of said bridge, and an inclined camming surface formed in the body-portion of said needle generally beneath said bridge, the upper edge of said bridge behind said abutment being twisted outwardly and being disposed at an angle to the side-surface of said body-portion and with the outer surface of said bridge also disposed at an angle to the side-surface of said body-portion to form the inclined camming surface in the outer side of said bridge.

JULIUS SIRNAY.
